EX

OR D 20,459

D20459

UNITED STATES PATENT OFFICE.

JOHN F. BRAYER AND EDWARD J. KING, OF ROCHESTER, NEW YORK, AS-SIGNORS TO THE CO-OPERATIVE FOUNDRY COMPANY, OF SAME PLACE.

DESIGN FOR A STOVE-SHELF AND SUPPORT.

SPECIFICATION forming part of Design No. 20,459, dated January 6, 1891.

Application filed June 25, 1890. Serial No. 356,730. Term of patent 7 years.

To all whom it may concern:

Be it known that we, JOHN F. BRAYER and EDWARD J. KING, citizens of the United States, residing at Rochester, New York, have 5 invented and produced a certain new and useful Design for a Stove-Shelf, of which the following is a specification, reference being had to the accompanying photograph, forming a part thereof.

10 The leading features of our present design are the standards C on the sides of the stove-pipe B and having at their upper ends a shelf A, and also the said standards and shelf, with the ornamentation hereinafter described.

15 The standards C extend upward from the bottom substantially straight and then project at the front forward to the point where they meet the underside of the shelf, forming brackets G. These standards are

20 slightly concavo-convex in cross-section, and are also formed of open-work, the vertical part consisting of the two straight moldings or borders D, slightly notched on their prox-

mate sides, as shown, and between these are arranged slightly rounded curved parent 25 stems E, having at intervals sprays or conventionalized folded leaves F springing from them, which also touch and are connected to the moldings D at the sides. The front or bracket portions G of the standards are also 30 of open-work, formed on the under side with an indentation and with the interior scrolls connected to the top of the forward moldings D. The bases of the standards C are provided with the angular corners rounded upward to 35 the part where the open-work begins, and upon these parts are provided ornaments c, substantially as shown.

What we claim is—

The design for stove-shelves and supports 40 herein shown and described.

JOHN F. BRAYER.

EDWARD J. KING.
